SUCTION CLEANING TOOL

Edward R. Swann, North Canton, and Brandt F. Ziegler,
Jr., Canton, Ohio, assignors to The Hoover Company,
North Canton, Ohio, a corporation of Ohio

Application April 6, 1956, Serial No. 40,960

Term of patent 14 years

(Cl. D9—2)

FIG. 1

FIG. 2

FIG. 3

Figure 1 is a side elevational view of a suction cleaning tool showing our new design;

Figure 2 is a rear perspective view thereof, and

Figure 3 is a front perspective view of the same.

The dominant features of the design reside in the portions of the drawing shown in solid lines.

We claim:

The ornamental design for a suction cleaning tool, substantially as shown and described.
